UNITED STATES PATENT OFFICE.

EMMOR BONSALL, OF DAVENPORT, IOWA.

LEARNER'S TELEGRAPHIC INSTRUMENT.

SPECIFICATION forming part of Letters Patent No. 336,284, dated February 16, 1886.

Application filed February 3, 1885. Serial No. 154,823. (No model.)

To all whom it may concern:

Be it known that I, EMMOR BONSALL, of Davenport, in the county of Scott and State of Iowa, have invented a new and Improved Telegraph-Instrument, of which the following is a full, clear, and exact description.

The object of my invention is to provide a new and improved telegraph-instrument for producing the clicks or sounds of the Morse characters on a Morse sounder by mechanical means, thus enabling students to produce the sounds easily and rapidly, and to learn to read letters, words, and messages transmitted by means of a Morse sounder.

15 The invention consists in the combination, with a frame having spring-contacts connected with the circuit-wires, of devices for pulling a slotted or recessed strip between the said spring-contacts, thus breaking and closing the circuit.

Reference is to be had to the accompanying drawings, forming a part of this specification, in which similar letters of reference indicate corresponding parts in all the figures.

25 Figure 1 is a plan view of my improved telegraph-instrument. Fig. 2 is a longitudinal sectional elevation of the same, on the line *x*, Fig. 1. Fig. 3 is a cross-sectional elevation of the same on the line *y*, Fig. 1. Fig. 30 4 is a similar sectional view to Fig. 2 of my invention, showing the rolls or points out of contact with the interposed pattern-strip, being opposite an aperture or perforation of the pattern-strip.

35 Two rollers, A A, are journaled in the upright part of the frame B, at one end of the same, both rollers being covered with rubber, and one of them having a crank-handle, I, for turning it. The frame B is provided in each 40 end with a guide-slot, C, in line with the space between the rollers. Binding-posts D are held on the top and bottom of the frame, at the end opposite the one at which the rollers A are located, and with each post a spring-contact,

45 F, is connected. On the free end of the lower spring, F, a roller, F', is pivoted, which is in electrical contact with the said spring. The line-wires G are held in the binding-posts, and a battery and a Morse sounder are in the circuit. Strips H, preferably made of paper or

other non-conducting material, are provided with a series of slots, J, which are arranged to correspond in their size and arrangement with the Morse characters. Any number of these strips may be used; but preferably thirty-two 55 of them are used, each having different characters. A strip, H, is passed through the slots C and between the rollers A, and is moved in the direction of the arrow *a* by turning the crank-handle I. The upper spring, F, rests 60 against the top of the strip H, and the roller F' in the lower strip rests against the bottom of the strip. When the ends of the springs come to a slot, J, the end of the upper spring can come in contact with the roller on the 65 lower spring, the circuit is closed, and the click is produced by the sounder, the clicks varying according to the size and arrangement of the slots. Then the contact is broken by the paper between two slots, and so on alternately. By moving the strips H through the 70 apparatus a number of times the clicks or letters are repeated, and the student can easily commit them to memory. The knowledge of manipulating the key is not required to produce the sounds, as all that is necessary is to turn the crank I.

In place of using paper strips H, metal strips may be used, which are either slotted in the manner shown, or have recesses in their upper surfaces. The springs rest against both surfaces of the strip, and thus the contact is closed; but when a slot comes between the points of the springs the circuit is broken, as the point of the top spring cannot work 85 down to the bottom of the recess or within the notch to come in contact with the roller F', the springs being arranged so that they will just be in contact with the surface of the strip, but will not spring together to come in contact with each other.

Having thus fully described my invention, I claim as new and desire to secure by Letters Patent—

1. In a telegraph-instrument, the combination, with a perforated pattern-strip of conducting material and its feeding-rolls, of the spring-arms connected to the line-wire binding-posts, and having their free ends or points arranged to stand out of contact as an aperture 95 100

or perforation of said strip is brought into coincidence with said points or ends of arms, the circuit being completed by the conductivity of the said strip and spring-arms, substantially as set forth.

5. 2. In a telegraph-instrument, the combination, with a perforated pattern-strip of conducting material and its feeding-rolls, of the spring-arms connected to the line-wire binding-

posts, and having their free ends or points, one of which is provided with a roll, arranged to stand out of contact as an aperture or perforation of said pattern-strip is brought into coincidence with said points or ends of arms, substantially as and for the purpose set forth.

Witnesses: EMMOR BONSALL.
